UNITED STATES PATENT OFFICE.

HENRY G. REIST, OF SCHENECTADY, NEW YORK, ASSIGNOR TO GENERAL ELECTRIC COMPANY, A CORPORATION OF NEW YORK.

FASTENING FIELD-MAGNETS TO SPIDERS.

SPECIFICATION forming part of Letters Patent No. 726,347, dated April 28, 1903.

Application filed October 18, 1901. Serial No. 79,142. (No model.)

To all whom it may concern:

Be it known that I, HENRY G. REIST, a citizen of the United States, residing at Schenectady, county of Schenectady, State of New York, have invented certain new and useful Improvements in Fastening Field-Magnets to Spiders, of which the following is a specification.

This invention relates to dynamo-electric machines; and its object is to provide improved means for attaching the field-magnets to the spider of a revolving-field machine. When rotating at high speeds, a strong centrifugal force is exerted on the field-magnets, so that they must be securely fastened to the spider to avoid accidents. I provide each magnet with a base-plate, which is firmly bolted to the rim of the spider.

In the accompanying drawings, Figure 1 is an end elevation of a portion of the revolving-field magnet of an alternating-current generator. Fig. 2 is a side elevation, partly in section. Fig. 3 is a bottom plan view of part of the clamping base-plate on an enlarged scale. Fig. 4 is a cross-section of the same on the line 4-4, Fig. 3. Fig. 5 is an end elevation similar to Fig. 1, showing a modified construction. Fig. 6 is a section of the same on an axial plane. Fig. 7 is a bottom plan view of the base-plate. Fig. 8 is a cross-section of the same on the line 8-8, Fig. 7.

The spider A has a cylindrical rim a, on which are secured the radially-projecting field-magnets B. Each magnet has a core or pole-piece b, preferably composed of laminations of sheet metal clamped together by end plates b' and bolts b². The outer end of the pole-piece has a laterally-extending flange b³ to confine the winding b⁴, which may be of any ordinary construction.

In order to fasten the magnets to the spider, the pole-pieces are attached to base-plates, which in turn are bolted to the rim of the spider. Various modes of attaching the pole-pieces to the base-plate may be devised; but I prefer the two illustrated in the drawings.

On Sheet 1 the pole-piece has a downwardly-extending portion b⁵, shaped to interlock with the base-plate. The portion b⁵ is preferably a dovetail rib, as shown, and the base-plate C has a correspondingly-shaped opening en-

gaging with said rib. The plate is made in two parts, being preferably halved on a central longitudinal line in order that it may be readily engaged with the rib. The two parts 55 are clamped together on the rib b⁵, as by transverse bolts c. At each end of the base-plate is a perforated lug c' to receive the bolts D, which fasten it to the rim of the spider.

In the modification shown on Sheet 2 the 60 pole-piece has a transverse hole b⁶, through which passes a bar E. The end plates b' are fastened to this bar by screws b⁷. The base-plate C' is solid and has holes c², preferably countersunk, as shown, to receive screws F, 65 which engage with tapped holes in the bar E, thus attaching the magnet to the base-plate, which is then bolted to the rim of the spider by bolts D, passing through the perforated lugs c'.

It will be observed that in both modifications the base-plate is clamped against the lower end of the pole-piece—in the first by the wedging action of the dovetail rib and the beveled edges of the base-plate, and in the 75 second by the screws pulling downward on the transverse bar.

What I claim as new, and desire to secure by Letters Patent of the United States, is—

1. Means for fastening a laminated pole-piece to a support, comprising a base-plate, means engaging the lower ends of laminations and clamping them to the said base-plate, and means for fastening the base-plate to the support.

2. Means for fastening a laminated pole-piece to a support, comprising a base-plate, devices for clamping said base-plate to the lower ends of laminations in said pole-piece, and means for fastening the base-plate to the 90 support.

3. The combination with the spider of a dynamo-electric machine, of a magnet thereon, a base-plate underlying said magnet and having perforated ears at its ends, means for attaching the base-plate to the pole-piece of the magnet, and bolts passing through the spider and the ears on the base-plate.

4. The combination with the spider of a dynamo-electric machine, of a magnet therefor having a pole-piece provided with an undercut rib, a base-plate having beveled edges to

engage with said rib, and means for fastening the base-plate to said spider.

5. The combination with the spider of a dynamo-electric machine, of a magnet therefor having a pole-piece provided with a dovetail rib, and a base-plate made in two parts, adapted to engage with said rib, and provided with means for fastening it to the spider.

6. The combination with the spider of a dynamo-electric machine, of a magnet therefor having a laminated pole-piece provided with

a dovetail rib, a base-plate made in longitudinal halves and having beveled inner edges to engage with said rib, transverse bolts to clamp said halves together, and bolts for fastening said base-plate to the spider. 15

In witness whereof I have hereunto set my hand this 15th day of October, 1901.

HENRY G. REIST.
